UNITED STATES PATENT OFFICE.

AUGUSTUS LEICESTER MOSS, OF SANDUSKY, OHIO.

SANDING DEVICE FOR AUTOMOBILES.

No. 807,186.

Specification of Letters Patent.

Patented Dec. 12, 1905.

Application filed February 8, 1905. Serial No. 244,727.

To all whom it may concern:

Be it known that I, AUGUSTUS LEICESTER Moss, a citizen of the United States, and a resident of Sandusky, in the county of Erie and 5 State of Ohio, have invented a new and Improved Sanding Device for Automobiles, of which the following is a full, clear, and exact description.

The object of the invention is to provide a 10 new and improved sanding device more especially designed for automobiles and similar vehicles to prevent the same from slipping while traveling over wet or slippery streets or roadways.

15 The invention consists of novel features and parts and combinations of the same, as will be more fully described hereinafter and then pointed out in the claims.

A practical embodiment of the invention is 20 represented in the accompanying drawings, forming a part of this specification, in which similar characters of reference indicate corresponding parts in all the views.

Figure 1 is a plan view of an automobile 25 provided with the improvement, parts being broken out. Fig. 2 is an enlarged sectional side elevation of the same. Fig. 3 is an enlarged transverse section of the sand-controlling valve, the section being on the line 3 3 of 30 Fig. 4. Fig. 4 is an enlarged plan view of the same, and Fig. 5 is an enlarged transverse section of one of the discharge-nozzles.

The sanding device is mounted on a suitable 35 part of an automobile A, and the sand to be scattered over the roadway in front of the drive-wheels A' of the automobile is held in a sand-container B, preferably in the form of a hopper connected at its lower end with a valve C, having an outlet D, from which branch 40 sand-pipes E in opposite directions, each pipe being provided at its outer terminal with a flat nozzle or spreader F for spreading the sand in a thin fan-like stream over the roadway in front of and around the drive-wheels 45 A', so that the latter take a firm grip to prevent the automobile from slipping, especially when traveling over wet asphalted streets or similar roadways. The valve C is also adapted to connect by a pipe G with a compressed-air 50 reservoir H, into which air is discharged by the outlet-pipe I, of an air-pump I of any approved construction and actuated by an eccentric I' or similar mechanism, adapted to be connected by a clutch J with the driven axle A', and other driven part of the automobile. 55

The valve C is provided with a valve-casing

C', (see Fig. 3,) containing a valve-plug C² formed in its top with a conical recess a, into the top of which open ports b, adapted to register with similar ports c, formed in a cap C³ held on the casing C', on which rests the lower end of the sand-container B. The lower end of the recess a terminates in a sidewise extension a', opening into the outlet-pipe D, and into the said extension a' opens a nozzle d, contained or formed in the plug C² and adapted to register with the pipe G, leading to the compressed-air reservoir H. Normally the valve-plug C² is in a closed position, so that the ports b are disconnected from the ports c, the extension a' is out of register with the pipe D, and the nozzle d is out of register with the pipe G.

When it is desired to make use of the sanding device, the plug C² is turned so as to bring 75 the several parts in register, as illustrated in Fig. 3, to allow the sand to flow from the container B to the registering ports c and b, into the recess a and to the extension a' thereof, in which the sand is engaged by a blast of 80 air from the nozzle d, so that the sand is forced through the pipe D and sand-pipes E into and through the nozzles F, whereby the sand is scattered over the roadway in front of and around the wheels A' for the latter to take a 85 firm grip, thus preventing slipping of the wheels.

In order to actuate the valve-plug C² by the chauffeur or other party in charge of the automobile, the following device is provided: On 90 the lower end of the valve-plug C² is secured an arm K, carrying at its free end a pin K', extending into an elongated slot L', formed in a rod L, extending lengthwise under the automobile, the forward end of the rod L being connected 95 with a lever N, having a foot-piece N' and adapted to be pushed forward by the chauffeur to impart a swinging motion to the lever N and a rearward motion to the rod L. A spring O is connected with the lever N to normally hold the foot-piece N' in a rearmost position. The rod L also controls the clutch J for connecting or disconnecting the eccentric I' with and from the axle A', and for this purpose the rear end of the rod L is provided with 100 a pin L', engaging one arm of a bell-crank lever P, having its other arm in the shape of a shifting-fork engaging the clutch J. (See Fig. 1.) A spring Q, somewhat weaker than the spring O, is connected with the bell-crank lever P, so as to hold the same in engagement 105 with the pin L', and when the rod L is moved

rearwardly on the forward pushing of the foot-piece N' then the spring Q acts on the bell-crank lever P to shift the clutch J in engagement with the eccentric I^2 to start the pump I with a view to pump air into the reservoir H . When the rod L moves rearwardly, the pump is started ahead of the turning of the valve-plug C^2 from a non-active into an active position, owing to the fact that the pin K' travels in the elongated slot L' until the forward end of the slot is reached, and then a further rearward movement of the rod L causes a swinging of the arm K to turn the valve-plug C^2 from the non-active or closed position to open position, as illustrated in Fig. 3. When this takes place, sand is forced by the air-blast onto the roadway in front of and around the wheels A' , as above described.

By the arrangement described the operator on pressing the foot-piece N' a short distance forward—that is, until the pin K' reaches the forward end of the slot L' —starts the pump I to fill the reservoir H with a predetermined pressure, governed by a safety-valve H' on the air-reservoir H . Thus the operator can charge the air-reservoir H at any time while the automobile is running without setting the sanding device in action. It is, however, expressly understood that when the operator pushes the foot-piece N' forwardly to its full extent then the pump I is started ahead of the sanding device to maintain the pressure in the reservoir H during the time the sanding device is used, so that at a critical time the sanding device does not fail to act by the absence of a proper air-blast to force the sand out of the nozzles.

After the slippery place has been passed the operator simply releases the pressure on the foot-piece N' , so that the lever N and rod L return to their normal positions by the action of the spring O , the rod L acting on the bell-crank lever P to move the clutch J out of engagement with the eccentric I^2 , and the rod L also causes a return of the plug C^2 back to its normal non-active position to cut off the air-blast and to cut off the sand-container from the pipe D .

It is understood that it is very important that a proper air-blast is had to positively force the sand onto the roadway, as described, and in order to produce the desired result the pump is started ahead of the turning of the valve-plug C^2 to accomplish the desired result.

The device is very simple and durable in construction, is composed of comparatively few parts, and is not liable to easily get out of order.

Having thus described my invention, I claim as new and desire to secure by Letters Patent—

1. An automobile provided with a sanding device having pipes terminating in nozzles and extending at an angle toward the path to be traveled by the driving-wheels but terminating away from the wheels, at the inner side of said path, for scattering sand over a road-

way in front of the driving-wheels of the automobile and across their pathway.

2. An automobile provided with a sanding device having pipes terminating in flat nozzles and extending forwardly and outwardly toward the path of travel of the driving-wheels but terminating away from the wheels at the inner side of said path, the nozzles being arranged to scatter sand in fan shape over a roadway in front of the driving-wheels of the automobile and across their pathway.

3. The combination with an automobile, of a sanding device comprising a sand-container, a compressed-air reservoir carried on the automobile, an air-pump for charging the said compressed-air reservoir with compressed air, nozzles for scattering sand over a roadway, in front of and around the driving-wheels of the automobile, a valve for controlling the connection between the said sand-container and the said nozzles and for controlling the connection between the compressed-air reservoir and the said nozzles, to force the sand out of the latter by compressed air from the said reservoir, and means under the control of the chauffeur for actuating in unison the said valve and the stopping and starting device of the said air-pump.

4. The combination with an automobile, of a sanding device held on the said automobile and comprising a sand-container, nozzles connected with the said container and arranged to scatter sand over a roadway in front of and around the driving-wheels of the automobile, a compressed-air reservoir, a pipe leading therefrom and a manually-controlled valve having a nozzle adapted to register with said pipe, the said valve simultaneously controlling the connection between the said nozzles and the said air-reservoir.

5. The combination with an automobile, of a sanding device held on the said automobile and comprising a sand-container, nozzles connected with the said container and arranged to scatter sand over a roadway, in front of and around the driving-wheels of the automobile, a compressed-air reservoir, a manually-controlled valve for simultaneously controlling the connection between the said nozzles and the said sand-container and between the said nozzles and the said air-reservoir, an air-pump having a stopping and starting device connected with a driven part of the automobile, and means under the control of the chauffeur and connected with the said stopping and starting device and with the said valve, for successively actuating the same.

6. The combination with an automobile, of a sanding device held on the said automobile and comprising a sand-container, nozzles connected with the said container and arranged to scatter sand over a roadway, in front of and around the driving-wheels of the automobile, a compressed-air reservoir, a manually-controlled valve for simultaneously controlling

the connection between the said nozzles and the said sand-container and between the said nozzles and the said air-reservoir, an air-pump having a stopping and starting device connected with a driven part of the automobile, and means under the control of the chauffeur and connected with the said stopping and starting device and with the said valve, for successively actuating the same, to start the pump ahead 10 of the opening of the said valve.

7. A sanding device provided with a valve having a valve-casing connected with a sand-container, a compressed-air reservoir, a pipe connecting said reservoir with the valve-casing, a sand-discharge leading from the valve-casing, and a valve-plug mounted to turn in the said casing and under the control of the operator, the valve-plug having an outlet adapted to register with the sand-discharge, 15 and a nozzle in the valve-plug registering with the outlet of the valve-plug and adapted to register with the pipe leading from the reservoir, the said valve-plug connecting the said discharge simultaneously with both the sand-container and the said compressed-air reservoir.

8. An automobile provided with a sanding device, an air-reservoir for delivering a blast of air to the said sanding device, a pump for 30 pumping air into the reservoir, and means under the control of the operator, for actuating the said sanding device, the said means also controlling the starting mechanism of the pump to start the same.

35 9. An automobile provided with a valve-controlled sanding device, an air-reservoir for delivering a blast of air to the said sanding device, a pump for pumping air into the reservoir, and means under the control of the operator, for actuating the said sanding device and for starting the said pump ahead of the said sanding device, the said means comprising a rod movable in the direction of its length and connected with the valve of the sanding device, the said rod also controlling the starting mechanism for the pump.

10. An automobile provided with a sanding device, a compressed-air reservoir for delivering a blast of air to the said sanding device, 50 a pump, mechanism for actuating the pump, a clutch for connecting said mechanism with a driven part of the automobile, for charging the said reservoir with compressed air, and means under the control of the operator, for actuating the said sanding device and for actuating said clutch to stop or start the pump.

11. An automobile provided with a sanding device comprising a sand-container mounted on the automobile and provided with an outlet, and pipes extending downwardly, outwardly and forwardly from the said outlet, the said pipes each extending at an angle toward the path to be traveled by the respective driving-wheels, but terminating short of 65 said path, for scattering sand over the road-

way in front of the driving-wheels and across the path of travel thereof.

12. An automobile provided with a sanding device comprising a sand-container mounted on the automobile and provided with an outlet and pipes branching in opposite directions from said outlet, the said pipes extending downwardly, outwardly and forwardly from the said outlet, the said pipes each extending at an angle toward the path to be traveled by the 70 driving-wheel but terminating short of said path, and each provided at its terminal with a flat nozzle for spreading the sand in fan shape over a roadway in front of the driving-wheels and across their path of travel. 75

13. A sanding device, comprising a sand-container, a valve for controlling the discharge of sand from said container, an air-reservoir connected with the sanding device, a pump for pumping air into the reservoir, mechanism for actuating the pump, a stopping and starting device for the pump, and means connected with the said valve to actuate the same, the said means also having a controlling connection with the stopping and starting device 80 for the pump. 85

14. A sanding device, comprising a sand-container, a valve for controlling the discharge of sand from said container, an air-reservoir for delivering a blast of air to the 95 said sanding device, a pump for pumping air into the reservoir, means for actuating the pump, a stopping and starting device for the pump, and a rod for actuating said valve and having a loose sliding connection with the 100 same, the said rod also controlling the stopping and starting device for the pump.

15. In a sanding device, the combination with a sand-container, of a valve-casing connected with the sand-container, a compressed-air reservoir connected with the valve-casing, a pump for pumping air into the reservoir, a stopping and starting device for the pump, a sand-discharge leading from the valve-casing, a valve-plug mounted to turn in the casing to connect the said discharge with the sand-container and with the compressed-air reservoir, an arm on the said valve-plug provided at its free end with a pin, a rod for actuating said valve and having an elongated slot 110 engaged by said pin, a lever connected with said rod, a spring connected with said lever, and a controlling connection between the said rod and the stopping and starting device for the pump. 115

16. The combination with a valve-controlled sanding device, of an air-reservoir for delivering air to the said sanding device, a pump for pumping air into the reservoir, means for actuating the valve of the sanding device, the 120 said means including a longitudinally-movable rod operatively connected with the said valve, mechanism for actuating the pump, a clutch for controlling said mechanism, a shifting-fork engaging the said clutch, a spring con- 125 130

nected with the shifting-fork for moving the clutch into active position, and a connection between the said longitudinally-movable rod and the shifting-fork for normally holding 5 the shifting-fork against the tension of its spring.

17. A sanding device comprising a sand-container, a valve-casing connected at its top by ports with the sand-container, a compressed-air reservoir connected by a pipe with the valve-casing, a sand-discharge pipe connected with the valve-casing, a valve-plug mounted to turn in the said casing and under the control of the operator, the said plug having a recess in its upper part into which open ports adapted to register with the ports in the top of the casing, the said recess terminating at its lower end in a side extension adapted to register with the discharge-pipe, and a nozzle 15 in said valve-plug opening into the said side ex- 20

tension and adapted to register with the pipe leading from the air-reservoir.

18. A sanding device comprising a sand-container, a compressed-air reservoir, an air-pump for charging the said reservoir with 25 compressed air, a sand-discharge, a valve for controlling the connection between the sand-container and the said discharge and for controlling the connection between the compressed-air reservoir and the said discharge, 30 and means for actuating in unison the said valve and the stopping and starting device for the air-pump.

In testimony whereof I have signed my name to this specification in the presence of two sub- 35 scribing witnesses.

AUGUSTUS LEICESTER MOSS.
